BAFFLE AND CLOSURE ASSEMBLY FOR FOOD WASTE DISPOSER

Clifton H. Ewing, Easthampton, Mass., assignor to Westinghouse Electric Corporation, East Pittsburgh, Pa., a corporation of Pennsylvania

Application September 30, 1955, Serial No. 537,690

4 Claims. (Cl. 4—189)

This invention relates to a food waste disposer, more particularly to a baffle and closure assembly for a food waste disposer supported from a kitchen sink with its inlet connected to the drain opening of the sink.

An object of the invention is to provide an improved baffle and closure assembly.

Another object is to provide a baffle and closure assembly which, at one time, serves as baffle means to prevent comminuted particles and water flying up out of the disposer while it is in operation and at the same time permits flow of water into the disposer to carry away the comminuted particles; which, at another time, provides a water-tight seal to permit holding water in the sink; as for washing dishes, and which, at still another time, permits access to the disposer for the purpose of inserting material to be comminuted and for removing articles that may have been inadvertently admitted thereto.

A further object is to provide a baffle and closure assembly that is simple, may be inexpensively manufactured and is easy to use.

The baffle and closure assembly of the present invention comprises a baffle element made of a resilient material, such as rubber. This element comprises an annular peripheral supporting portion adapted to be mounted in the inlet opening of the disposer and a plurality of resilient finger-like elements extending radially inwardly. The assembly further includes a disc-like closure member or lid adapted to seat on the peripheral supporting portion, which forms a seat for the closure member. The peripheral supporting portion is provided with a number of upstanding projections which are circumferentially spaced from each other and which are disposed outwardly of the seat. The closure is provided with a number of circumferentially spaced projections which extend radially beyond the seat and which are adapted, in one angular position of the closure member, to interleaf with the projections on the peripheral supporting portion to permit the closure to rest on the seat to provide a seal, and in another angular position of the closure member, to rest upon the projections of the peripheral supporting portion, in which case the closure is held in raised position and permits flow of water into the disposer during operation thereof in order to carry away the comminuted particles.

These and other objects are effected by the invention as will be apparent from the following description taken in connection with the accompanying drawings, forming a part of this application, in which:

Fig. 1 is a vertical section showing the upper portion of a food waste disposer connected to a sink, and also showing the baffle and closure assembly of the present invention with the closure or lid in the raised position;

Fig. 2 is a perspective view of the baffle element;

Fig. 3 is a perspective view of the closure member;

Fig. 4 is a vertical section showing the baffle and closure assembly in the closed or seal position;

2

Fig. 5 is a horizontal section taken on the line V—V of Fig. 4, showing the lid in the raised position;

Fig. 6 is a similar view showing the baffle element, the lid being removed;

Fig. 7 is a similar view with the lid in the closed position; and

Fig. 8 is a vertical section showing a modified form of baffle element.

Referring to the drawing in detail, the upper portion of the housing 10 of the food waste disposer is connected to the sink 11, in communication with the drain opening therein, by a mounting structure which includes an adapter ring or sleeve 12. The latter includes a substantially cylindrical portion having at its upper end a flange 13 resting on the adjacent portion of the sink 11. A supporting ring 14 rests on a split ring 15 seated in a groove in the adapter ring 12, and a flange 16 at the upper end of the housing 10 is bolted to the ring 14, with a rubber gasket 17 therebetween.

The baffle and closure assembly of the present invention comprises a plate-like baffle element 18 and a closure member or lid 19. The baffle element 18 is made of a resilient material, such as synthetic rubber, and includes an annular, peripheral supporting portion 21, which rests on a shoulder on the interior of the ring 12 adjacent its lower end, and whose outer cylindrical surface fits snugly against the inner or concave cylindrical surface of the ring. It further comprises an annular series of resilient fingers 22 which extend radially inwardly from the annular supporting portion 21. The supporting portion 21 is formed with an annular rib 23, which forms a seat for the lid 19. It is reinforced by a metal ring 24 and is formed with a groove to receive the ring. In the form shown in Fig. 4, the groove opens radially inwardly, whereas in the form shown in Fig. 8 the groove opens radially outwardly. The ring is preferably of plated brass and may be of any cross sectional form to provide desired strength. It may, if desired, be molded into the supporting portion 21.

The supporting portion 21 of the baffle element is further provided with three circumferentially extending and circumferentially spaced upstanding projections 25, disposed outwardly of the bead 23.

The lid 19 has an imperforate portion of sufficient diameter to seat on the bead 23 and thus to provide a seal or water-tight closure. It is also provided with three circumferentially spaced projections 26. The dimensions of the projections 25 and 26 are such that, in one angular position of the lid as shown in Fig. 7, the projections 26 of the lid interleave with the projections 25 of the baffle, so that the lid rests on the bead 23, and, when the lid is rotated through an angle of, for example, 30 degrees, the projections 26 of the lid rest on the projections 25 of the baffle to hold the lid in raised position. In this position, water may flow through the spaces between the projections and between the lid and the inner surface of the adapter ring 12, and through the openings in the baffle element into the interior of the disposer.

The upstanding projections 25 and 25a may be inclined upwardly and outwardly as shown in Fig. 8 to provide an outward bias against the inner surface of the sleeve 12, thereby retaining the baffle element 18 or 18a against the force of bones thrown upwardly against it. While the upstanding projections 25 and 25a are shown as integral with the supporting portion 21, it will be apparent that they are not necessarily so, but may be separate therefrom and united by a ring to retain them in proper relative position.

The embodiment shown in Fig. 8 represents principally a variation in form of the baffle element, which is here designated 18a. As mentioned, the groove for re-

ceiving the reinforcing ring 24 opens outwardly, and the upstanding projections are inclined outwardly. This embodiment also comprises an inclined seat 23a for the closure, instead of the rib 23.

Operation or use

In the use of the disposer, the lid 19 is removed from the adapter ring 12, whereupon material to be comminuted may be inserted in the housing 10, during which time the fingers 18 flex freely to permit such insertion. The lid is then placed in the raised position shown in Figs. 1 and 5, in which space for the passage of water is provided. Continuous flow of water into the disposer from the sink is provided and operation of the disposer is started. The water flowing through the disposer carries away the comminuted particles as operation continues. Operation of the disposer causes particles to be thrown upwardly with some force, but these particles strike either the rubber baffle 18 or the lid 19 and then drop again by gravity or are carried downwardly by the flow of water. Should it be desired to admit additional material to be comminuted, the lid 19 may be lifted out of the ring 12, the material inserted and the lid replaced. As long as the lid 19 is removed, one may feed material continuously into the disposer during the operation thereof.

When it is desired to retain the water in the sink, as for washing dishes, the lid is merely rotated until interleaving of the projections permits it to move downwardly and rest on the seat provided by the bead 23.

The baffle element 18 may be easily removed for cleaning under the faucet, and may then readily be replaced merely by pushing it down into place, where it frictionally engages the inner surface of the cylindrical portion of the ring 12.

From the above description, it will be apparent that I have provided an assembly which is simple and inexpensive to manufacture, which is understandable by everybody and easy to use, and which has no moving parts. It will also be apparent that when the baffle element requires replacement, it may easily be removed and a new element installed.

While the invention has been shown in several forms, it will be obvious to those skilled in the art that it is not so limited, but is susceptible of various other changes and modifications without departing from the spirit thereof.

What is claimed is:

1. A baffle and closure assembly for a food waste disposer comprising a plate-like baffle element of resilient

material having an annular supporting portion and a plurality of flexible fingers extending radially inwardly from the supporting portion, said supporting portion including a seat for a closure, circumferentially spaced

5 upstanding projections disposed outwardly of said seat, said upstanding projections being maintained in predetermined relation to each other, a closure adapted to rest on said seat, and having cooperating projections adapted, in one angular position of the closure, to interleave with

10 the first-mentioned projections to permit the closure to rest on said seat and, in another angular position of said closure, to rest on said upstanding projections to support the closure in raised position.

2. A baffle and closure assembly for a food waste dis-

15 poser comprising a plate-like baffle element of resilient material having an annular supporting portion and a plurality of flexible fingers extending radially inwardly from the supporting portion, said supporting portion including a seat for a closure, and having circumferentially

20 spaced upstanding projections disposed adjacent said seat, a closure adapted to rest on said seat and having cooper-

25 ating projections adapted, in one angular position of the closure, to interleave with the first-mentioned projections to permit the closure to rest on said seat and, in another

angular position of said closure, to rest on said up-

standing projections to support the closure in raised po-

sition.

3. An assembly as set forth in claim 2 and further

including an adapter ring comprising a substantially cy-

30 lindrical portion, an outwardly extending flange at the

upper end thereof, and an inwardly projecting shoulder

at the lower end thereof, said supporting portion resting

on said shoulder and engaging the inner or concave sur-

face of said cylindrical portion.

35 4. An assembly as set forth in claim 3 wherein the

outer surfaces of said upstanding projections are inclined

upwardly and outwardly to resiliently engage said inner

or concave surface of said cylindrical portion.
